UNITED STATES PATENT OFFICE.

SAMUEL SEGAL, OF NEW YORK, N. Y., ASSIGNOR TO BURGLAR PROOF LOCK COMPANY,
INC., OF NEW YORK, N. Y., A CORPORATION OF NEW YORK.

LOCK.

1,087,839.

Specification of Letters Patent. Patented Feb. 17, 1914.

Application filed May 29, 1913. Serial No. 770,750.

To all whom it may concern:

Be it known that I, SAMUEL SEGAL, a citizen of the United States, residing at New York city, in the county of New York and State of New York, have invented new and useful Improvements in Locks, of which the following is a specification.

The invention relates to attachments for locks and has for its object to provide a simple and efficient means for connecting the lock casing and keeper, whereby, to prevent the prying open of a door from its casing, by the use of a burglar's tool or the like.

To these ends the invention consists in the novel details of construction and combination of parts more fully hereinafter described and particularly pointed out in the claims.

Referring to the accompanying drawings forming a part of this specification in which like numerals designate like parts in all the views:—Figure 1 is a perspective view of a lock of the Yale type showing my invention applied thereto. Fig. 2 is a horizontal sectional view of a portion of a door and casing with the parts shown in Fig. 1 secured to position thereon, and also showing parts of the lock broken away for the sake of clearness, and Fig. 3 is a detail perspective view of the angular tie strip.

Referring to the drawings in detail 1 indicates a portion of a door to which is secured the lock casing 2, 3 indicates a portion of the door casing to which is secured the keeper 4, and 5 indicates a tie strip for connecting the lock casing and keeper when the door is in the closed and locked position.

The tie strip is preferably formed of thin sheet metal and provided at one end with an aperture 6 for receiving a stud 7 for pivotally connecting the strip to the front wall of the lock casing 2, as shown. The other or free end of the strip extends beyond the end of the lock casing and is bent inwardly as at 8, for the purpose of entering the keeper through the slot 9 formed in the front wall thereof.

An opening 10 is arranged within the inwardly extending portion of the tie strip

and is of such size as to receive the bolt 11 when it passes into the keeper. Thus, it will be seen that the presence of the angular-shaped tie strip operates to unite the lock casing and keeper when the parts are connected and locked as shown in Figs. 1 and 2.

By means of the upwardly projecting lug 12 formed on the lock casing it will be seen that the angular tie strip is normally held in horizontal position and that the bolt receiving portion of the strip is properly guided into and out of the keeper when the door is opened and closed. A small knob 13 or handle is also provided on the free end of the angular strip for the purpose of throwing it into and out of operative relation with the keeper when desired.

From the foregoing it will be seen that by the use of an improved lock constructed in accordance with my invention, it will be practically impossible to spring the lock casing from its keeper as is now done by burglars by the insertion of a tool between the door and its casing.

It is obvious that those skilled in the art may vary the details of construction and arrangements of parts without departing from the spirit of my invention and therefore I do not wish to be limited to such features except as may be required by the claims.

What is claimed as new is:

1. Means for connecting the lock casing and keeper, comprising an angular-shaped tie strip pivotally connected at one end to the lock casing and having its other end adapted to be detachably interlocked with the keeper, said strip being also adapted to be thrown into and out of operative relation with the keeper.

2. In combination with a lock casing and a keeper having a lateral opening; of an angular-shaped tie strip pivotally connected at one end to the lock casing and having its other end interlocked within the keeper by passing through the lateral opening thereof.

3. In combination with a lock casing and a keeper having a lateral opening; of an angular-shaped tie strip pivotally connected at one end to the wall of the casing and

having its other end interlocked within the keeper by passing through the lateral opening thereof, said tie strip being provided with an opening in the last-named end for receiving the lock bolt, and a lug mounted on the lock casing for holding the tie strip in operative relation with the keeper.

In testimony whereof I affix my signature in presence of two witnesses.

SAMUEL SEGAL.
